PIN-TYPE ADJUSTING DEVICES FOR DRESS FORMS

Frank Crohn, Chicago, Ill.

Application December 28, 1955, Serial No. 555,850

2 Claims. (Cl. 223—68)

2

portion of the bar is pivoted to the section 11 on a rivet 16, while the section 10 receives a keeper 18 through which the opposite end portion of the bar 15 is slidable, such keeper having base flanges 19 which are secured to the section 10 by rivets 20.

Fig. 3 shows that the major portion of the bar 15 is made with a longitudinal series of apertures 25. The section 10 receives a pin 26 from the outside, such pin having an external head 28 which seats in a cavity 29 made in the outer surface of the section. The free end of the pin 26 is adapted to pass through any one of the apertures 25 in the bar 15, according to the spacing of the sections 10 and 11. Fig. 6 shows the pin 26 passing through the bar as stated. No locking device is necessary for the pin 26, since the dress form is a stationary piece of equipment, and no influence would develop to back the pin out of the bar 15. Necessarily, the cavity 29 is sufficiently wider than the head 28 for grasping the same with the fingers.

It is now apparent that the pin 26 is not only a handy external control which eliminates the need of reaching into the form for the control of the adjusting device, but a very simple stop for setting the adjusting device at any point to which the sections 10 and 11 are spaced. The adjusting device employs a minimum number of parts and is therefore of a nature to be produced at very low cost.

While I have described the invention along specific lines, various minor changes or refinements may be made therein without departing from its principle, and I reserve the right to employ all such changes and refinements as may come within the scope and spirit of the appended claims.

I claim:

35. 1. An adjusting device for the adjoining sections of a dress form comprising a bar spanning the sections along the inner side, means to attach one end portion of the bar to one of the sections, the bar having a longitudinal series of apertures opposite the other section, and a pin passed through the latter from the outside for direct selective engagement with one of such apertures according to the spacing of the sections, said pin having a head at its outer end and being freely insertible into and removable from the form.

40. 2. The structure of claim 1, said other section having a cavity in its outer surface around the pin, and the head of the latter seating against the floor of such cavity flush with the outer surface of the dress form on such engagement.

My invention relates to dress forms of the sectional type, that is, where the sections are assembled edge-to-edge and separable from each other when the size of the form is to be enlarged at one or more points to fit the size of the garment which is patterned on the form. Adjusting devices for the sections are provided on the inside of the form, but frequently are difficult to reach by way of the bottom, armpit or other openings in the form. Also, such adjusting devices often become dust-laden or corroded, making it a disagreeable task to handle or manipulate the same. In view of these conditions, it is one object of the present invention to provide an external control for an adjusting device of the type under consideration, such control being in the form of a headed pin.

A further object is to design the adjusting device in the form of a bar which spans the sections adjoining each other and is formed to cooperate with the headed pin previously referred to.

An additional object is to construct an adjusting device which is of exceeding simplicity.

With the above objects in view, a better understanding of the invention may be had by reference to the accompanying drawing, in which—

Fig. 1 is a perspective view of a typical dress form equipped with the novel adjusting device;

Fig. 2 is an enlarged elevation of a horizontally positioned adjusting device as applied to one region of the form;

Fig. 3 is a view of the showing in Fig. 2 from the inside of the form;

Fig. 4 is an enlarged section on the line 4—4 of Fig. 3; and

Figs. 5 and 6 are, respectively, sections taken on the lines 5—5 and 6—6 of Fig. 4.

Referring specifically to the drawing, the variously grouped sections of the form are illustrated in Fig. 1, and two adjoining sections 10 and 11 are shown in Fig. 2. Since this view is from the front, or outside of the form, most of the adjusting device seen in Fig. 2 appears in dotted lines.

As more clearly shown in Figs. 3 and 4, the main part of the adjusting device is a bar 15 of flat stock which spans the sections on the inner side. Thus, one end
